UNITED STATES PATENT OFFICE.

JOSIAH A. DEWEY, OF SAN FRANCISCO, CALIFORNIA, ASSIGNOR TO DEWEY DAVENPORT COMPANY, OF SAN FRANCISCO, CALIFORNIA, A CORPORATION OF CALIFORNIA.

COUCH-BED.

1,302,774.

Specification of Letters Patent.

Patented May 6, 1919.

Application filed January 25, 1916. Serial No. 74,118.

To all whom it may concern:

Be it known that I, JOSIAH A. DEWEY, a citizen of the United States of America, and a resident of the city and county of San Francisco, State of California, have invented a new and useful Couch-Bed, of which the following is a specification.

My invention relates to combination beds and couches.

10 An object of the invention is to provide a couch structure of very compact form which is adapted to be unfolded into a bed of standard size.

15 Another object of the invention is to provide a structure of the class described which includes a deep coil spring mattress for the top mattress to rest upon.

20 Another object of the invention is to provide a couch bed of the class described in which the mattress for the bed serves also as the yielding seat of the couch when the structure is folded.

25 The invention possesses other features of advantage which, with the foregoing, will be set forth in the following description of the preferred form of my invention which is illustrated in the drawings accompanying and forming part of the specifications. It is to be understood that I do not limit myself 30 to the showing made by the said drawings and description, as I may adapt variations of the preferred form within the scope of my invention as set forth in the claim.

Referring to the drawings:

35 Figure 1 is an end elevation of the couch bed of my invention when folded together into compact form.

Fig. 2 is an end elevation of the couch bed showing the structure partly unfolded.

40 Fig. 3 is an end elevation of the couch bed fully unfolded to provide a full size bed.

Fig. 4 is a fragmentary left side elevation.

Fig. 5 is a fragmentary right side elevation.

45 Fig. 6 is a detail view showing the folding leg of the structure.

Fig. 7 is another detail of the leg showing it in its folded position.

My invention comprises a couch frame

50 upon each of the sides of which is pivoted a mattress supporting frame. The pivotal supports of these mattress frames are so arranged on the couch frame and with relation to each other that the two frames are supported within the couch frame, one above the

other, when the structure is folded into its most compact form as shown in Fig. 1; but when it is desired to unfold the structure to provide a bed, the upper frame is temporarily displaced about its pivots to permit 60 the lower frame to be transposed outwardly from the couch frame and inverted, the upper frame then being dropped back to its original position and forming with the lower frame a continuous supporting frame for the 65 mattresses. The top of the lower frame and the bottom of the upper frame may be formed so that they constitute a seat and back for the structure when the parts are in the position shown in Fig. 2. A coiled spring 70 mattress of ample depth is disposed upon each frame and a top mattress is arranged upon the coil spring mattress. When the lower frame is transposed and inverted into its unfolded position, the structure provides 75 a bed of full size as shown in Fig. 3 with top mattress and coiled spring mattress of the usual depth and comfort.

The two ends of the couch frame are alike, and each is formed of the member 2 stiffened near the bottom by the end rail 3 rigidly fastened thereto. The two ends of the couch frame are secured together by the side rails 4 and 5. Two mattress supporting frames 6 and 7 are provided of such size that 80 they are adapted to lie one above the other within the space defined by the couch frame. Frame 6 is pivotally mounted upon the couch frame by means of a heavy fitting or fixture 8 which is bolted to each end of the 85 frame adjacent one of its sides and which is pivoted upon the member 2 at the point 9. The fitting 8 is provided with an arm 12 which extends downwardly below the frame 6 when the latter is in its folded position. A 90 long coiled spring 13 connects the end of the arm 12 to the member 2 on the opposite side of the couch frame and this spring is put under tension as the frame 6 is turned to its folded position as shown in Fig. 2 and to its 95 transposed or extended position shown in Fig. 3, thus acting as a counterbalance to the weight of the frame in both positions so that only a minimum of effort is needed to move the frame from one position to the other. A 100 series of coiled springs 14 are arranged upon the frame 6 to form a spring mattress in the well known manner, the springs being disposed upon the under side of the frame when 105 in the folded position, so that when the 110

frame is turned about its pivots to its transposed inverted position, the spring mattress is above the frame.

A leg 16 is pivoted at 17 on the outer side of the frame 6 near each end. In both the extended position of the leg shown in Fig. 6 and the folded position shown in Fig. 7, a stop pin 18 positions the leg with respect to the frame.

- 10 From the above, it is seen that the mattress supporting frame 6 together with its coiled spring mattress 14 is pivotally mounted upon the couch frame ends and may be swung to folded position within the couch frame or transposed to an inverted position without the couch frame, the weight of the frame at the beginning and ending of the movement to both positions being counterbalanced by the coil springs 13.
- 15 The mattress supporting frame 7 is non-invertible, but is of similar structure to frame 6 and is also provided with a coiled spring mattress. The springs 19 comprising this mattress are arranged on the top surface of the frame so that they also provide a spring mattress for the seat or yielding surface of the structure when it is used as a couch. The frame 7 is provided at each end with a fitting 21 bolted to the frame and pivoted to the lower end rail 3 at 22. The shape and proportions of the fitting 21, its position on the frame 7 and the position of the pivot on the end rail, are such as to permit the frame 7 to be supported above and closely adjacent to frame 6 when all are folded together within the couch frame and to permit it to be turned upwardly and outwardly about its pivots to a vertical position without the couch frame, at which point it clears all the rest of the structure and leaves an unobstructed path for the unfolding or transposing and inverting movement of the lower frame 6. On the inside of the fitting 8 and axially aligned with the pivot 9 is arranged a boss 24, Fig. 4, upon which the edge of the frame 7 rests in its lowered position. Since the boss is aligned with the pivot 9, it is in position to support the free end of the frame 50 7 whether frame 6 is within or without the couch frame. An extension 25 of the fitting 21 is connected by a coil spring 26 to a point on the couch frame remote from the pivot 22 and this spring is placed under tension when the frame 7 is lowered from its vertical position shown in Fig. 2, thus counterbalancing the weight of the frame and rendering it easy to raise and lower. A fitting 27 reinforces the attachment of

the side rail 5 to the member 2 and is provided with a stop 28 against which the fitting 21 abuts when the frame 7 is raised to the vertical position. The fitting 27 also carries an upstanding lug 29 upon which the free end of the frame 6 rests when it is folded within the couch frame.

Relative to the couch frame the frame 7 occupies the same position in the couch form of the structure as it does in the bed form, its swinging movement to a vertical position and back being merely to permit the lower frame to be moved about its pivots.

A top mattress in two parts 31 and 32 is provided and these parts are preferably secured one upon the other to the spring mattress 19. The mattresses 31 and 32 are fastened together along the edge 33 and the edges of the lower mattress 31 are secured to the wire edge of the spring mattress 19 by tapes 34 so that the mattress 31 is retained upon the spring mattress 19 when the latter is raised to the vertical position.

In the couch form of the structure as shown in Fig. 1, the two top mattresses 31 and 32 are superposed upon the spring mattress 19 and form the seat or yielding surface of the couch and the whole may be covered by a suitable spread or drapery. When the couch is to be converted into a bed, the upper bed section which includes the frame 7 is raised to the vertical position and the lower bed section which includes the frame 6 transposed outwardly to its inverted position. The upper bed section is then turned down to its original position and the top mattress 32 turned back upon the wire mattress 14, thus providing a full size bed with top mattress and wire mattress of sufficient depth to give the maximum of softness and resiliency.

I claim:

A couch bed comprising a couch frame, an invertible lower bed section pivoted to said couch frame, a non-invertible upper bed section provided with rigid extension 105 arms, said arms being pivoted intermediate their ends to said couch frame below the plane of the pivots of said invertible bed section, and springs connecting the free ends of said arms to said couch frame.

In testimony whereof, I have hereunto set my hand at San Francisco, California, this 19th day of January, 1916.

JOSIAH A. DEWEY.
